SWITCH ACTUATING MECHANISM

Waldo J. Kelleigh, Wayland, Mass., assignor to
General Control Company, Boston, Mass., a
corporation of Massachusetts

Application June 29, 1949, Serial No. 102,089

16 Claims. (Cl. 200—153)

1

This invention relates to actuating mechanisms and more particularly to mechanisms which during successive operations thereof alternately actuate and release a switch or other device.

Objects of this invention are to provide a mechanism which during a first operation thereof actuates a switch or other associated device, which maintains such device in an actuated status until operated a second time, which releases such device upon a second operation thereof, which is rapid and positive in operation, which does not jam, which is rugged and trouble free, which requires a minimum of moving parts, which has a long operating life, which is simple to manufacture, and which advances the mechanical art generally.

In a broad aspect the invention contemplates a mechanism comprising two movable members which are positioned relatively to each other with their respective paths of travel intersecting. One or both of the members are arranged to operate an associated device near the end or other portion of their path of travel. Such device may be switch contacts, a switch of the quick acting snap action type, or other mechanically operated apparatus for example a latch, detent or valve. Biasing, which may be either the force supplied by a spring or by gravity, is employed to urge the members towards one limit of their respective paths of travel. The mechanism is operated by an actuator which during successive strokes thereof alternatively moves the members from the biased limit to an opposite limit of their respective paths of travel. The members are arranged so that the first member moved to such opposite limit by the first stroke of the actuator is maintained at such limit by the second member. The succeeding stroke of the actuator moves the second member to the opposite limit of its path thereby releasing the first member so that it returns to the biased limit of its path wherein it maintains such second member at the opposite end of its travel.

In one aspect the movable members may be slidably mounted with their paths symmetrically arranged with respect to the path of travel of a reciprocating actuator. The actuator is provided with a pivoted cam portion for alternatively contacting cammed portions of the respective movable members. The members are also provided with detent portions whereby the first member moved to the limit opposite the biased limit by the first stroke of the actuator is maintained at such limit until released by the second member as it is subsequently moved towards

2

its opposite limit by the second stroke of the actuator.

In another aspect the members are rotatable, being pivotally arranged relatively to each other so that their arcuate paths of travel intersect, these paths preferably being arranged symmetrically with respect to the path of a reciprocating actuator. The actuator has a pivotally arranged portion for alternatively contacting the cammed portions of the respective members so that the first member contacted is rotated to the limit opposite the biased limit of its path of travel. The first member is maintained at such limit by a detent portion provided upon the second member. The succeeding stroke of the actuator rotates the second member to the opposite limit of its path thereby releasing the first member so that it returns to the biased limit of its path wherein a detent portion thereupon maintains the second member at the opposite limit of its travel.

A feature of the invention is a body or frame cast or otherwise formed with two spaced bosses whereupon are pivotally secured the rotatable members. The bosses are joined by a connecting portion or bridge having an aperture wherein is reciprocatingly disposed an actuator, the axis of such aperture being normal to a plane through the axes of the respective bosses. The switch or other device operated by the mechanism is attached to the opposite side of the body from the rotatable members. The torque for actuating the device is transmitted from one of the rotatable members through a shaft projecting through a centrally located aperture in the correlated boss, which shaft also acts as a pivot for such member.

A feature of another embodiment of the invention is a channel shaped frame having a web whereupon are mounted the rotatable members, the actuator and one or more stationary electrical contacts. One or both of the members may carry a respective moving electrical contact for making contact with the corresponding stationary contacts when the respective rotatable members are at one limit of their paths of travel.

These and other objects, aspects and features will be apparent from the following description of several illustrative specific embodiments of the invention referring to drawings in which:

Fig. 1 is a front elevation view of one embodiment with the actuator positioned at the start of a stroke;

Fig. 2 is a view similar to Fig. 1 with the actuator at the end of the stroke for which it is positioned in Fig. 1;

Fig. 3 is a view similar to Fig. 1 with the actuator at the start of the second stroke;

Fig. 4 is a plan view of the same embodiment;

Fig. 5 is a side elevation of the embodiment shown in Fig. 4;

Fig. 6 is a rear elevation of the embodiment shown in Fig. 4;

Fig. 7 is a section on line 7—7 of Fig. 1;

Fig. 8 is a modification of the embodiment shown in Figs. 1 to 7 wherein movable switch contacts are carried by the rotatable arms;

Fig. 9 is a section on line 9—9 of Fig. 8;

Fig. 10 is an isometric view of one of the movable contact arms;

Fig. 11 is a modification of the embodiments shown in Figs. 1 to 10 wherein the arms operate an associated mechanical device;

Fig. 12 is a front elevation view of a further embodiment wherein the electrical contacts are carried upon the movable arms and which is of particularly simple construction permitting the shaping of most parts from sheet material;

Fig. 15 is a view similar to Fig. 14 with the actuator at the end of the stroke for which it is positioned in Fig. 14;

Fig. 16 is a view similar to Fig. 14 with the actuator at the start of a second stroke; and

Fig. 17 is a side elevation of the embodiment shown in Figs. 14 to 16.

The embodiment of the invention shown in Figs. 1 through 7 is a mechanism for operating a switch S. The mechanism comprises a frame or body 20 preferably cast from a metal such as aluminum and having two bosses 21 (Fig. 4) joined by a connecting portion or bridge 22. The body 20 is further strengthened by two flanges 23 extending normally from the bridge 22 at the outer portion of the respective bosses 21.

As is best shown in Fig. 5, each boss 22 has an axially disposed aperture therethrough wherein is journaled a shaft 24. The ends of the shafts 24 have threaded recesses in each of which there is secured a respective cap screw 26 by means of a lock-washer 27 having a greater diameter than the recesses in the bosses 22 so that the shafts 24 are axially restrained therein. Inserted under the head of one of the screws 26 is an arm 31 (Fig. 6) having a tab 32 projecting normally therefrom to engage the actuating pin 33 for the switch S which is attached to the rear of the body 20 by means of four screws 34.

Secured to the front end of the shafts 24 are two similarly shaped rotatable members such as the arms 36 which are distinguished from one another by the subscripts *a* and *b* respectively. Each of the arms 36 has an aperture in the upper end thereof through which projects the correlated screw 26 so that the associated lock washer 27 forces the arm against the abutting end of the shaft 24, thus preventing relative rotation therebetween. The opposite end of each of the arms 36 is provided with a projecting finger 37, the upper side of which is shaped to provide a cammed portion 38 whose use will be described hereinafter. The bottom of each cam forms a detent portion. The arms 36 are biased towards each other by means of a spring 40, the ends of which are secured in apertures in the respective arms.

The details of construction of an actuator 41 for rotating the arms 36 against the biasing action of the spring 40 are best shown in Fig. 7.

The actuator 41 comprises a plunger 42 which is reciprocatingly disposed within an aperture 43 in the bridge 22 (see also Fig. 4). The diameter of the plunger 42 is reduced as at 47 to accommodate a spring 46 having one end abutting the shoulder resulting from the reduction in plunger diameter and the other end abutting the shoulder 48 formed by a reduction in diameter of the aperture 43 so that the spring exerts an upward biasing force upon the actuator 41. The diameter of the plunger 42 is further reduced as at 49 so that it may project through an aperture 41 in the bottom portion of the bridge 22. A stop is provided for the actuator 41 by a washer 52 which is slipped over the projecting end 49 of the plunger 41 and held in place by peening as at 53.

The cammed portions of the arms 36 are contacted by a face such as the end of finger 54 projecting from an arm 55 pivotally secured to the plunger 42 by means of a screw 56. Inserted between the arm 55 and the plunger 42 is a spacer 57, the plunger being slotted as at 58 to provide a flat bearing surface for the end of the spacer. The opposite end of the arm 55 is engaged by the centrally disposed coils of a spring 59 which extends between the flanges 23 so that the pivotal portion is biased in a central position.

The above described embodiment operates as follows. The switch S is in its normal condition when the arm 31 is in the raised position shown in Fig. 6 corresponding to the position of arms 36a and 36b shown in Fig. 1 wherein the arm 36b is urged by the spring 40 to what may be termed the biased limit of its path of travel. The arm 36a is simultaneously held at the opposite limit of its travel by the detent portion 39 of the arm 36b hence the arms remain in a state of stable equilibrium. The actuator 41 is biased upwardly by the spring 46 so that the finger 54 is not in contact with either of the arms 36a or 36b.

As the actuator 41 is forced downwardly, the finger 54 contacts the cammed portion of the arm 36b rotating such arm in its path of travel until its opposite limit of travel is reached as is shown in Fig. 2, which limit is determined by the movement of the actuator. Such movement of the arm 36b releases the arm 36a so that it is urged by the spring 40 to the biased limit of its travel. This movement of arm 36a rotates the shaft 24 thus moving the arm 31 (Fig. 6) to depress the switching actuating pin 33. Upon the return of the actuator 41 to its upper biased position, the detent portion 39 of the arm 36a maintains the arm 36b at the opposite limit of travel so that the arms remain in the state of stable equilibrium shown in Fig. 3. In this state the pin 33 is depressed to maintain the switch S with its contact in the transferred position until the arms are returned to the previously described state shown in Fig. 1 by a subsequent stroke of the actuator 41.

In Figs. 8 and 9 is shown a second embodiment of the invention wherein the switch S is replaced by the movable contacts 60. Each contact 60 (Fig. 10) comprises a contact point 61, for example of a silver alloy, welded, riveted or otherwise secured to one flange of a channel member 62. The other flange of the channel member 62 is fastened to an arm 63 of insulating material which replaces the arm 31. An aperture 64 is provided in one end of the arm 63 so that the end thereof accommodates the screw 26 securing the arm to the abutting end of the shaft 24.

The frame 20 is also altered in this embodiment having cast integral therewith two projecting tabs 66 whereupon a panel 68 of plastic or other insulating material is fastened by the screws 67. Two sets of stationary contacts 69 for cooperating with the respective movable contacts 60 are mounted upon the insulating panel 68.

The operation of the actuator 41 in this embodiment alternatively to move the arms 36a and 36b between the states of stable equilibrium at the limits of their paths of travel is the same as that described heretofore in connection with the first embodiment. The movement of the arms 36 rotates the shafts 24 so that the attached movable contacts 60 make and break with the stationary contacts 69. In the embodiment illustrated the contacts are arranged so that one set is open and the other set closed in one state of equilibrium, this contact relationship reversing upon the movement of the arms 36 to the other state of equilibrium. It will be obvious, however, that by means of other contact configurations both sets of contacts can be arranged to be closed or opened in either state of equilibrium of the arms 36.

A third embodiment is shown in Fig. 11 wherein the panel 68 is eliminated and the movable contacts 60 are replaced by the arms 71 which rotate back and forth in response to the movement of the actuator 41 as was described in detail heretofore. Pivotedly attached to the end of the arm 71 is a rod 72 for actuating an associated mechanical device (not shown) for example a valve or detent of conventional construction which is alternatively opened and closed by successive strokes of the actuator 41.

In Figs. 12 and 13 a fourth embodiment comprises two arms 36a' and 36b' pivotally attached by the screws 26' to a web 22' of a channel shaped frame 20' formed from sheet metal by bending the flanges 23' at right angles to the plane of the web 22'. Each of the pivoted ends of the respective arms 36a' and 36b' is provided with an aperture for a respective screw 26' which also projects through an aperture in a spacer 25 to engage a threaded hole in the web 22'. The opposite end of the arm 36b' has cammed and detent portions 38' and 39' which cooperate with similar portions in the end of the arm 36a' in the same manner as the corresponding portions 38 and 39 cooperate as was described in detail heretofore.

Biasing for the arms 36a' and 36b' is again supplied by a spring 40 which interconnects the arms. A pivotal arm 55' for contacting the cammed arm portions 38' is fastened to an actuator 41' by a pin 56'. The actuator 41' is reciprocatingly attached to the web 22' by means of the rivets 73 which project through an elongated slot in the actuator to engage the web. The actuator 41' is biased upwardly by the restoring force of a leaf spring 74.

The arms 36a' and 36b' each carry a respective movable contact 75 thereupon which mate with the correlated stationary contacts 76 mounted upon the web 22' by means of the insulating plates 77. The arms 36a' and 36b' are alternatively shifted from a state of equilibrium at one limit of their respective paths of travel to another state of equilibrium at the opposite limit thereof in a manner analogous to that described in detail heretofore with reference to the other embodiments of the invention by the downward movement of the actuator 41'. Such movement may be accomplished either by manually pushing upon a lip 78 or automatically by means of an electric solenoid 80, as is shown in Fig. 13. As the actua-

tor 41' is depressed, the first stroke thereof opens one set of contacts 75-76 and conjointly closes the other set of contacts in which position the contacts remain until the actuator is again depressed. The second actuator stroke opens the closed contacts and closes the open contacts thereby restoring the original configuration. Subsequent strokes of the actuator 41' repeat the above contact operating cycle.

In Figs. 14 through 17 is shown another embodiment of the invention wherein the movable members 81 have a reciprocating linear travel rather than the rotary movement common to the above described embodiments. The members 81 are in the form of rods which are slidably restrained in aligned circular apertures in ways 82 fastened to a base plate 83. The members 81 are biased towards each other by means of springs 84 positioned circumjacent the respective members so that one end of each spring bears against a respective way 82. The other end of each spring 84 bears against a collar 86 fastened to the correlated rod member 81 so that the rod member is biased upwardly.

The rod members 81a and 81b are provided with cammed portions such as the conical recesses 87 in the upper ends thereof for cooperating with a pivotal portion of an actuator 88. The pivotal portion comprises a pin 89 one end of which is tapered to engage the conical recesses 87. The other end of the pin 89 is secured to a block 91 which is pivotally fastened in a slot in the end of a sliding member 92 by means of a pin 93 (Fig. 14). The pivotal portion is biased to a central position by means of a spring 94 recessed in an aperture in the sliding member 92 behind a pin 96 bearing against the block 91.

The sliding member 92 is guided in ways 97 and a cover plate 98 fastened thereto by means of screws 99. The actuator 88 is biased in an upward position by means of a leaf spring 101 which bears against the end portion of the sliding member 92 below the block 91. The opposite end of the member 92 is provided with a handle 100 whereby it may be manually depressed to operate the mechanism.

In Fig. 14 the mechanism is shown at the beginning of the first stroke of the actuator 88 with a switch S' operated thereby in its normal position. The rod member 81b is urged upwardly by the spring 84b towards the spring biased limit of its travel. The rod member 81a is at the opposite limit of its travel being held in such position against the force exerted by the spring 84a by the contact of the end of the rod member with the side of the rod member 81b which acts as a detent. The conical recess 87 in the end of the rod 81b is in the path of the actuator 88 so that as the actuator descends during the first stroke, the tapered end of the pin 89 contacts the recess thereby moving the rod member to the opposite limit of its travel as shown in Fig. 15. In such position a chamfered edge of the collar 86 intercepts an actuating pin 102 thereby transferring the contacts of the switch S'.

As the rod member 81b is moved downwardly its side portion which acts as a detent no longer restrains the rod member 81a so that the member 81a is moved upwardly to the spring biased limit shown in Fig. 15 wherein it restrains the member 81b as the actuator 41' is moved upwardly as is shown in Fig. 16. In this position the contacts of the switch S' remain transferred until the rod members 81a and 81b are again returned to the positions shown in Fig. 14 by a subsequent stroke of the actuator 88.

It should be understood that the present disclosure is for the purpose of illustration only and that this invention includes all modifications and equivalents which fall within the scope of the appended claims.

I claim:

1. A mechanism for operating an associated device comprising two movable members positioned relatively to each other with their respective paths of travel intersecting, one of said members operating said device during its travel, biasing means for urging the members towards one limit of travel of their respective paths, and an actuator mounted for movement in a path intersecting said paths and having a face for contacting and for alternatively moving said members from the biased limit to an opposite limit of their respective paths upon alternately contacting said members with said face during successive strokes of the actuator in its path, said members being arranged so that the first member is moved to said opposite limit by contact with said face during one stroke of the actuator and maintained at such limit by the second member, the succeeding stroke of the actuator in the same direction as the preceding stroke moving said second member to the opposite limit of its path thereby releasing said first member so that it returns to the biased limit of its path wherein it maintains the second member at such opposite limit of its path of travel.

2. A mechanism for operating an associated device comprising two similarly shaped movable members positioned relatively to each other with their respective paths of travel intersecting, one of said members operating said device during its travel, spring biasing means for yieldably urging the members towards one limit of travel of their respective paths, and an actuator mounted for movement in a path intersecting said paths and having a face for contacting and for alternatively moving said members from the spring biased limit to an opposite limit of their respective paths upon alternately contacting said members with said face during successive strokes of the actuator in its path, said members being arranged so that the first member is moved to said opposite limit by contact with said face during one stroke of the actuator and maintained at such limit by the second member, the succeeding stroke of the actuator in the same direction as the preceding stroke moving said second member to the opposite limit of its path thereby releasing said first member so that it returns to the spring biased limit of its path wherein it maintains the second member at such opposite limit of its path of travel.

3. A mechanism for operating an associated device comprising two movable members having similar paths of travel and positioned relatively to each other with their respective paths intersecting, one of said members operating said device during its travel, biasing means for urging the members towards one limit of travel of their respective paths, and an actuator mounted for movement in a path intersecting said paths and having a face for contacting and for alternatively moving said members from the biased limit to an opposite limit of their respective paths upon alternately contacting said members with said face during successive strokes of the actuator in its path, the paths of travel of said respective members being arranged symmetrically with respect to the actuator path so that the first member is moved to said opposite limit by contact with said face during one stroke of the actuator

and maintained at such limit by the second member, the succeeding stroke of the actuator in the same direction as the preceding stroke moving the second member to the opposite limit of its path thereby releasing said first member so that it returns to the biased limit of its path wherein it maintains the second member at such opposite limit of its path of travel.

4. A mechanism for operating an associated device comprising two movable members slidably arranged relatively to each other with their respective paths of travel intersecting, one of said members operating said device during its travel, biasing means for urging the members towards one limit of travel of their respective paths, and a reciprocating actuator mounted for movement in a path intersecting said paths and having a pivotally arranged portion with a face for contacting and alternatively moving said members from the biased limit to an opposite limit of travel of their respective paths upon alternately contacting said members with said face during successive strokes of the actuator, said members being arranged so that the first member is moved to said opposite limit by contact with said face during one stroke of the actuator and maintained at such limit by the second member, the succeeding stroke of the actuator in the same direction as the preceding stroke moving the second member to the opposite limit of its path thereby releasing said first member so that it returns to the biased limit of its path wherein it maintains the second member at such opposite limit of its path of travel.

5. A mechanism for operating an associated device comprising two movable members slidably arranged relatively to each other with their respective paths of travel intersecting, each of said members having a cammed portion and a detent portion, one of said members operating said device during its travel, biasing means for urging the members towards one limit of travel of their respective paths, and a reciprocating actuator mounted for movement in a path intersecting said paths and having a pivotally arranged portion with a face for alternatively contacting the cammed portions of the respective members thereby alternatively to move said members from the biased limit to an opposite limit of travel of their respective paths upon alternately contacting said members with said face during successive strokes of the actuator, said members being arranged so that the first member is moved by the pivotal portion of the actuator to said opposite limit by contact with said face during one stroke of the actuator and maintained at such limit by the detent portion of the second member, the succeeding stroke of the actuator in the same direction as the preceding stroke moving the second member to the opposite limit of its path thereby releasing said first member so that it returns to the biased limit of its path wherein its detent portion maintains the second member at such opposite limit of its path of travel.

6. A mechanism for operating an electric switch comprising two similarly shaped movable members slidably arranged relatively to each other with their respective paths of travel intersecting, each of said members having a cammed portion and a detent portion, one of said members operating said switch during its travel, spring biasing means for yieldably urging the members towards one limit of travel of their respective paths, and a reciprocating actuator mounted

for movement in a path intersecting said paths and having a pivotally arranged portion spring biased alternatively to contact the cammed portions of the respective members thereby alternatively to move said members from the biased limit to an opposite limit of travel of their respective paths upon successive strokes of the actuator, the paths of travel of said respective members being arranged symmetrically with respect to said path of travel of said actuator so that the first member moved by the pivotal portion of the said actuator to the opposite limit by one stroke of the actuator is maintained at such limit by the second member, the succeeding stroke of the actuator moving the second member to the opposite limit of its path thereby releasing said first member so that it returns to the biased limit of its path wherein it maintains the second member at such opposite limit of its path of travel.

7. A mechanism for operating an associated device comprising two rotatable members pivotally arranged relatively to each other with their respective paths of travel intersecting, one of said members operating said device during its travel, biasing means for urging the members towards one limit of travel of their respective paths, and a reciprocating actuator mounted for movement in a path intersecting said paths and having a face for contacting and having a pivotally arranged portion for alternatively rotating said members from the biased limit to an opposite limit of travel of their respective paths upon alternately contacting said members with said face during successive strokes of the actuator, said members being arranged so that the first member is rotated to said opposite limit by contact with said face during one stroke of the actuator and maintained at such limit by the second member, the succeeding stroke of the actuator in the same direction as the preceding stroke rotating the second member to the opposite limit of its path thereby releasing said first member so that it returns to the biased limit of its path wherein it maintains the second member at such opposite limit of its path of travel.

8. A mechanism for operating an associated device comprising two rotatable members having arcuate paths of travel and positioned relatively to each other with their respective paths intersecting, one of said members operating said device during its travel, biasing means for urging the members towards one limit of travel of their respective paths, and a reciprocating actuator having a pivotally arranged portion mounted for movement in a path intersecting said paths and having a face for contacting and alternatively rotating said members from the biased limit to an opposite limit of travel of their respective paths upon alternately contacting said members with said face during successive strokes of the actuator, the paths of travel of said respective members being arranged symmetrically with respect to the path of the actuator so that the first member is rotated to said opposite limit by contact with said face during one stroke of the actuator and maintained at such limit by the second member, the succeeding stroke of the actuator in the same direction as the preceding stroke rotating the second member to the opposite limit of its path thereby releasing said first member so that it returns to the biased limit of its path wherein it maintains the second member at the opposite limit of its travel.

9. A mechanism for operating an associated

device comprising two rotatable members pivotally arranged relatively to each other with their respective paths of travel intersecting, each of said members having a cammed portion and a 5 detent portion, one of said members operating said device during its travel, biasing means for urging the members towards one limit of travel of their respective paths, and a reciprocating actuator mounted for movement in a path intersecting said paths and having a pivotally arranged portion with a face for alternatively contacting the cammed portions of the respective members thereby alternatively to move said members from the biased limit to an opposite limit of travel of their respective paths upon alternately contacting said members with said face during successive strokes of the actuator, said members being arranged so that the first member is moved by the pivotal portion of the actuator 15 to said opposite limit by contact with said face during one stroke of the actuator and maintained at such limit by the detent portion of the second member, the succeeding stroke of the actuator in the same direction as the preceding stroke moving the second member to the opposite limit of its path thereby releasing said first member so that it returns to the biased limit of its path wherein its detent portion maintains the second member at such opposite limit of its path of travel.

10. A mechanism for operating an associated device comprising two rotatable members having arcuate paths of travel and positioned relatively to each other with their respective paths intersecting, one of said members operating said device 20 during its travel, spring biasing means for yieldably urging the members towards one limit of travel of their respective paths, and a reciprocating actuator mounted for movement in a path intersecting said paths and having a pivotally arranged portion for alternatively rotating said members from the spring biased limit to an opposite limit of travel of their respective paths upon alternately contacting said members during successive strokes of the actuator, the paths of travel 25 of said respective members being arranged symmetrically with respect to the path of the actuator so that the first member is rotated to said opposite limit by one stroke of the actuator and maintained at such limit by the second member, the succeeding stroke of the actuator in the same direction as the preceding stroke rotating the second member to the opposite limit of its path thereby releasing said first member so that it returns to the biased spring limit of its path 30 wherein it maintains the second member at such opposite limit of its path of travel.

11. A mechanism for operating associated devices comprising two rotatable members pivotally arranged relatively to each other with their respective paths of travel intersecting, each of said members alternatively operating during its travel, one of the respective devices, biasing means for urging the members towards one limit of travel of their respective paths, and a reciprocating actuator mounted for movement in a path intersecting said paths and having a pivotally arranged portion with a face for contacting and alternatively rotating said members from the biased limit to an opposite limit of travel of their respective paths upon alternately contacting said members with said face during successive strokes of the actuator, said members being arranged so that the first member is rotated to said opposite limit by the pivotal portion upon one stroke of the actuator and maintained at such limit by the

11

second member, the succeeding stroke of the actuator in the same direction as the preceding stroke rotating the second member to the opposite limit of its path thereby releasing said first member so that it returns to the biased limit of its path wherein it maintains the second member at such opposite limit of its path of travel.

12. A mechanism for operating a switch comprising two rotatable members having arcuate paths of travel and positioned relatively to each other with their respective paths intersecting, one of said members changing the position of said switch during its travel, biasing means for urging the members towards one limit of travel of their respective paths, and a reciprocating actuator mounted for movement in a path intersecting said paths and having a pivotally arranged portion with a face for contacting and alternatively rotating said members from the biased limit to an opposite limit of travel of their respective paths upon alternately contacting said members with said face during successive strokes of the actuator, the paths of travel of said respective members being arranged symmetrically with respect to the path of the actuator so that the first member is rotated to said opposite limit by one stroke of the actuator and maintained at such limit by the second member thus holding the switch in the transferred position, the succeeding stroke of the actuator in the same direction as the preceding stroke rotating the second member to the opposite limit of its path thereby releasing said first member so that it returns to the biased limit of its path wherein it maintains the second member at such opposite limit of its path of travel.

13. A mechanism for operating an associated device comprising a body including two spaced bosses and a connecting portion joining the bosses, said connecting portion having an aperture with an axis normally disposed to a plane through the axes of said bosses, two rotatable members pivotally secured to the respective bosses so that their respective paths of travel intersect one of said members operating said device during its travel, biasing means for urging the members towards one limit of travel of their respective paths, and an actuator reciprocatingly disposed in said body aperture in a path intersecting said paths and having a pivotally arranged portion with a face for contacting and alternatively rotating said members from the biased limit to an opposite limit of travel of their respective paths upon alternately contacting said members with said face during successive strokes of the actuator, said members being arranged so that the first member is rotated to said opposite limit by one stroke of the actuator and maintained at such limit by the second member, the succeeding stroke of the actuator in the same direction as the preceding stroke rotating the second member to the opposite limit of its path thereby releasing said first member so that it returns to the biased limit of its path wherein it maintains the second member at such opposite limit of its path of travel.

14. A mechanism for operating a switch comprising a body having the switch mounted upon one side thereof, said body including two spaced bosses having respective axial apertures therethrough and a connecting portion joining the bosses, said connecting portion having an aperture with an axis normally disposed to a plane through the axes of said bosses, two shafts journaled in the respective boss apertures, two similarly shaped rotatable members secured to

12

the respective ends of said shafts projecting from the bosses upon the opposite side of said body from said switch so that the respective paths of travel of the members intersect, an arm secured to the opposite end of one of said shafts for operating said switch, a biasing spring connecting the members for urging the members towards one limit of travel of their respective paths, an actuator reciprocatingly disposed in said body aperture in a path intersecting said paths and having a pivotally arranged portion, and a biasing spring for yieldably maintaining said pivotal portion parallel to the path of the actuator, said members having cammed and detent portions respectively whose arcuate paths of travel are symmetrically arranged with respect to the path of the actuator whereby the pivotal portion of the actuator alternatively contacts said cammed portions thereby to rotate said members from the spring biased limit to an opposite limit of travel of their respective paths upon successive strokes of the actuator so that the first member is rotated to said opposite limit by one stroke of the actuator to actuate the switch and maintained at such limit by the second member, the succeeding stroke of the actuator in the same direction as the preceding stroke rotating the second member to the opposite limit of its path thereby releasing said first member so that it returns to the biased limit of its path to release the switch wherein the first member maintains the second member at such opposite limit of its path of travel.

15. A mechanism for operating electrical contacts comprising a body having an insulation portion whereupon is mounted one of said contacts, said body including two spaced bosses having respective axial apertures therethrough and a connecting portion joining the bosses, said connecting portion having an aperture with an axis normally disposed to a plane through the axes of said bosses, two shafts journaled in the respective boss apertures, two similarly shaped rotatable members secured to the respective ends of said shafts projecting from the bosses upon the opposite side of said body from said contacts so that the respective paths of travel of the members intersect, an arm carrying a second contact secured to the opposite end of one of said shafts, a biasing spring connecting the members for urging the members towards one limit of travel of their respective paths, an actuator reciprocatingly disposed in said body aperture in a path intersecting said paths and having a pivotally arranged portion, and a biasing spring for yieldably maintaining said pivotal portion parallel to the path of the actuator, said rotatable members having cammed and detent portions respectively whose arcuate paths of travel are symmetrically arranged with respect to the path of the actuator whereby the pivotal portion of the actuator alternatively contacts said cammed portions thereby to rotate said members from the spring biased limit to an opposite limit of travel of their respective paths upon successive strokes of the actuator so that the first member is rotated to said opposite limit by one stroke of the actuator to close the contacts and maintained at such limit by the second member, the succeeding stroke of the actuator in the same direction as the preceding stroke rotating the second member to the opposite limit of its path thereby releasing said first member so that it returns to the biased limit of its path to open the contacts wherein the first

13

member maintains the second member at such opposite limit of its path of travel.

16. A mechanism for operating electrical contacts comprising a channel shaped body having a web portion with two flanges upon the opposing sides thereof respectively, said web portion also having attached thereto one of the contacts, two similarly shaped rotatable members pivotally secured to the web portion, one of said members carrying a second contact, a biasing spring connecting the members for urging the members towards one limit of travel of their respective paths, an actuator reciprocatingly attached to said web portion for movement in a path intersecting said paths and having a pivotally arranged portion, and a biasing spring for yieldably maintaining said pivotal portion parallel to the path of the actuator, said rotatable members having cammed and detent portions respectively whose arcuate paths of travel are 20 symmetrically arranged with respect to the path of the actuator whereby the pivotal portion of the actuator alternatively contacts said cammed portions thereby to rotate said members from the spring biased limit to an opposite limit of travel of their respective paths upon successive strokes of the actuator so that the

14

first member is rotated to said opposite limit by one stroke of the actuator to close the contacts and maintained at such limit by the second member, the succeeding stroke of the actuator in the same direction as the preceding stroke rotating the second member to the opposite limit of its path thereby releasing said first member so that it returns to the biased limit of its path to open the contacts wherein the first member maintains the second member at such opposite limit of its path of travel.
